ATTORNEY.

UNITED STATES PATENT OFFICE.

THOMAS M. KENT, OF BALTIMORE, MARYLAND.

DESIGN FOR A PICTURE-FRAME.

SPECIFICATION forming part of Design No. 24,453, dated July 2, 1895.

Application filed May 27, 1895. Serial No. 550,868. Term of patent 3½ years.

To all whom it may concern:

Be it known that I, THOMAS M. KENT, a citizen of the United States, residing at Baltimore, in the State of Maryland, have invented and 5 produced a new and original Design for Picture-Frames, of which the following is a specification.

The accompanying drawing shows a front view of the design.

10 The essential features of my design consist in a rectangular frame having at each of its straight sides an ovolو-shaped piece, the several ovolو-shaped pieces when viewed *ensemble*, being arranged to produce a broken oval 15 or elliptical outline, thus presenting to the eye the appearance or effect of a rectangular frame resting on or in front of an oval frame.

15 The letter A designates the rectangular frame of a given color and having four straight 20 sides b, forming a border to inclose any picture. Extended outward from each straight

side b of the frame is an ovolو-shaped piece C of a color contrasting with that of the rectangular frame, and these several pieces are arranged to form a broken oval or elliptical 25 outline, from the broken portions of which the angular corners d of the rectangular frame project, thus presenting to the eye the appearance or effect of a rectangular frame resting on or in front of an oval frame. The 30 ovolو-shaped pieces are ornamented by repoussé work, while the rectangular frame is plain-surfaced.

I claim—

The design for a picture-frame as herein 35 shown and described.

In testimony whereof I affix my signature in the presence of two witnesses.

THOMAS M. KENT.

Witnesses:

WILLIAM H. BERRY,
C. CALVERT HINES.
